CLAIM

The ornamental design for a container for film spool, as shown and described.

DESCRIPTION

FIG. 1 is a perspective view of a container for film spool showing my new design;

FIG. 2 is a top plan view thereof;

FIG. 3 is a bottom plan view thereof;

FIG. 4 is a front elevation thereof, with a strap attached;

FIG. 5 is a rear elevation thereof;

FIG. 6 is a right side elevation thereof, the left side elevation being a mirror image thereof;

FIG. 7 is a perspective view thereof, in open position; and

FIG. 8 is a top plan view of FIG. 7.

FIG. 1

FIG. 6

FIG. 2

FIG. 5

FIG. 3

FIG. 4

FIG. 7

FIG. 8
